UNITED STATES PATENT OFFICE.

JOHN S. ROWELL, OF BEAVER DAM, WISCONSIN.

WHEEL.

SPECIFICATION forming part of Letters Patent No. 625,419, dated May 23, 1899.

Application filed September 30, 1898. Serial No. 692,328. (No model.)

To all whom it may concern:

Be it known that I, JOHN S. ROWELL, a citizen of the United States, and a resident of Beaver Dam, in the county of Dodge and State 5 of Wisconsin, have invented certain new and useful Improvements in Wheels; and I do hereby declare that the following is a full, clear, and exact description thereof.

My invention has for its object to provide 10 simple, economical, and strong wood-spoke vehicle-wheels devoid of wood fellies, but organized with especial reference to durability under any climatic conditions to which they may be subjected and to the substitution of 15 new spokes by unskilled labor.

Therefore said invention consists in certain 20 peculiarities of construction and combination of parts hereinafter particularly set forth with reference to the accompanying drawings 25 and subsequently claimed.

Figure 1 of the drawings represents an elevation of one of my improved vehicle-wheels partly broken away to show the connection 25 of a spoke-ferrule with the rim; Fig. 2, a sectional view illustrating a rim-coupling constituting part of the wheel; Fig. 3, an outer side view of the coupling-sections; Fig. 4, a detail view of a spoke and ferrule, the latter being in section; and Fig. 5, an inner end view of a 30 ferrule.

Referring by letter to the drawings, A indicates a hub of any preferred material and construction provided with sockets for a series of ordinary wood spokes B, devoid of 35 outer end tenons, inasmuch as they do not connect with wooden fellies. Driven close on the outer end of each spoke is a malleable-iron casting in the form of a ferrule C, having its closed end provided with an 40 outwardly-projecting center lug b, that engages a corresponding aperture in a split rim D, of steel.

Riveted to the ends of the rim, inside the same, are malleable-iron castings in the form 45 of plates E F, each of which has a pair of inwardly-extending apertured lugs c for the engagement of a curved bolt G, and a clamp-nut H is run on the bolt against one of the plate-lugs. The plate E is provided with an

end tongue d, that engages a corresponding 50 groove e, formed in the meeting end of the plate F, and this tongue-and-grooved union of the plates prevents the rim D from being shakily, said plates, the bolt, and nut constituting a clamp-coupling by which said rim 55 is drawn tight to hold the spokes firmly in place, it being evident that screwing up on said nut will shorten the diameter of the aforesaid rim, and thereby exert pressure on said spokes in a direction toward the hub, this 60 pressure being gradual and equal on each spoke.

The ferrules being closed at their outer 65 ends, moisture cannot be absorbed in the corresponding ends of the spokes, and there being a pair of lugs on each clamp-plate screwing up of the nut has a tendency to straighten the bolt engaging said lugs, this straightening operating to exert draw in the joint of the clamp, it being possible to obtain pressure 70 enough to bow the spokes by slight adjustment of said nut.

The bolt is a standard machine-bolt and may be duplicated at any hardware store in case of fracture, and duplicate spokes being 75 had it is a simple matter for any one to remove the rim and replace a spoke or spokes.

Having thus described my invention, what I claim as new, and desire to secure by Letters Patent, is—

A wheel having wooden spokes tipped by closed-end metal ferrules provided with outer lugs, a metal split rim having apertures engaged by the ferrule-lugs, a pair of plates fast on the inside of the rim ends and in tongue-and-grooved connection with each other, a pair of apertured lugs extending inward from each plate, a curved bolt extending through all the plate-lugs, and a nut run on the bolt against one of said lugs.

In testimony that I claim the foregoing I have hereunto set my hand, at Beaver Dam, in the county of Dodge and State of Wisconsin, in the presence of two witnesses.

J. S. ROWELL.
